UNITED STATES PATENT OFFICE.

FRANCIS LINCOLN YOUNG, OF LONDON, ENGLAND, ASSIGNOR TO THE AEOLIAN COMPANY, OF NEW YORK, N. Y., A CORPORATION OF CONNECTICUT.

DEVICE FOR MARKING PERFORATED MUSIC-SHEETS WITH A LINE INDICATING AN EFFECT TO BE PRODUCED.

SPECIFICATION forming part of Letters Patent No. 692,969, dated February 11, 1902.

Application filed November 15, 1901. Serial No. 82,394. (No model.)

To all whom it may concern:

Be it known that I, FRANCIS LINCOLN YOUNG, a citizen of the United States, residing at London, England, have invented certain new and useful Improvements in Devices for Marking Perforated Music-Sheets with a Line Indicating an Effect to be Produced in Playing, of which the following is a specification.

10 My invention relates to a device for marking perforated music-sheets used in mechanically-played instruments with a line which indicates an effect that is to be produced in the playing of the music.

15 The object of my invention is to provide a controller of a mechanism comprised in such instrument with a suitable device which, during the passage of a perforated music-sheet over a tracker-board, will apply or de-
20 lineate a mark or line on the music-sheet which will indicate an effect to be produced in the replaying of the musical composition. The music-sheet so marked may be used as a stencil-sheet from which other music-sheets 25 having cut in them the same musical composition may be marked with the same line.

I will describe a musical instrument embodying my invention and then point out the novel features thereof in the claims.

30 In the accompanying drawings, Figure 1 represents a front elevational view of a mechanical musical instrument embodying my invention. Fig. 2 is a transverse section of the same. Fig. 3 is a detail view of a portion of a 35 perforated music-sheet having a line marked thereon which is intended to indicate effects to be produced in playing.

Similar letters of reference designate corresponding parts in all the figures.

40 A represents a portion of a mechanical musical instrument. The form of instrument here shown is a pianola, though my invention is equally applicable to other forms of mechanical musical instruments. As the form 45 of instrument here shown is well known to those skilled in the art it will not be described in detail. A' represents the tracker-board of such an instrument.

A² represents a perforated music-sheet,

movable over the tracker-board and which 50 controls the primary pneumatics of the instrument.

a a' represent the usual spools for the perforated music-sheet.

B B' B² represent controllers, each of which 55 is here shown as being in the form of a lever, and which controllers are provided at the front of the musical instrument. The controller B is for operating mechanism to move the loud or forte pedal. The controller B' is for operating mechanism which controls the high and low tension winds for obtaining differences in expression, and the lever or controller B² is for controlling the tempo mechanism which, as is well known, controls the speed of the 65 music-sheet in its passage over the tracker-board.

b represents the usual tempo-scale em-
ployed in connection with the controller B².

C represents an arm provided at one of its 70 ends with a socket c, in which a crayon, pencil, or other marking device is adapted to be held. This arm is adapted to be connected to either of the controllers B B' B², or there may be a separate arm for each or for two of 75 the controllers. The arm is here shown as being hinged at c' to the controller, and it is of such a length as to have the crayon, pencil, or other marking device approximately over the tracker-board, which to a certain ex- 80 tent will form a support. The marking device is held onto the perforated music-sheet by means of a spring c², one end of which is connected to a controller and the other to the arm C. 85

The operation of this device is as follows: A perforated music-sheet, or it may be a stencil-sheet, is placed in position in the instrument and the winding mechanism started to draw the perforated music-sheet over 90 the tracker-board. The operator, who is preferably a skilled musician, with the original composition before him, moves the arm C, and with it the marking device carried thereby, to produce the line a². To assist in moving the arm C, a handle C⁴ may be provided. It is obvious that as the arm C is moved trans- 95 versely of the music-sheet when marking a

line it will also move the controller, and thereby affect the mechanism which the controller governs. The line a^2 will be irregular, as will be seen at Fig. 3, and the irregularities 5 are due to the difference in effects to be produced in playing. After the irregular line has been applied it may be straightened. The straight portions between the oblique parts mean that one effect is to be produced as long 10 as the line is straight, and the oblique parts mean that a change in effect is to be made. It will be seen, therefore, that the operator will be enabled to accurately mark the perforated music-sheet to obtain the different 15 effects indicated in the original composition.

In illustrating the invention the arm C is shown as being applied to the controller B², which controller governs the tempo mechanism of the mechanical musical instrument.

20 I intend to cover generically by my claims the combinations specified by them, including, among other things, a line to indicate any and all effects to be produced—as, for example, a line to indicate the application of

25 the forte-pedal, another line to indicate the application of the expression instrumentalities, and another line to indicate speed or tempo.

Having thus described my invention, what 30 I claim is—

1. The combination with a perforated music-sheet of means for moving said sheet, and means for marking a line thereon during the movement of said sheet to indicate effects to 35 be produced in playing.

2. In a mechanical musical instrument, the combination of a perforated music-sheet, means for moving said music-sheet, a marking device operated during the playing of the 40 instrument and delineating upon the music-sheet a line corresponding to characteristics of the playing.

3. In a mechanical musical instrument, the combination of a perforated music-sheet, 45 means for moving said music-sheet, a control-

ler for a mechanism comprised in said musical instrument, and a marking device operated from said controller, for delineating a line upon the music-sheet which corresponds to characteristics in the playing to be produced by the mechanism of said controller. 50

4. In combination with the tempo mechanism of a mechanical musical instrument having a lever for controlling the same, a perforated music-sheet movable over the tracker-board of the mechanical instrument and a marking device carried by the lever of the tempo mechanism for applying a tempo-line to the music-sheet as it moves over the tracker-board. 55

5. In combination with the tempo mechanism of a mechanical musical instrument having a lever for controlling it, a perforated music-sheet movable over the tracker-board of the musical instrument, a lever-arm carried 65 by said lever and a marking device carried by said lever-arm for applying a tempo-line to the music-sheet as it moves over the tracker-board.

6. In combination with the tempo mechanism of a mechanical musical instrument, a music-sheet, a lever controlling said mechanism on the operation of which the speed of the tempo mechanism may be varied and consequently the speed of the music-sheet, and 70 means carried by said lever which marks on the music-sheet the changes to be made in the speed of the music-sheet.

7. In combination with a perforated music-sheet, of means for moving said sheet and 80 means for applying a tempo-line thereto during the movement of the music-sheet.

In testimony whereof I have signed my name to this specification in the presence of two subscribing witnesses.

FRANCIS LINCOLN YOUNG.
